WRIST WATCH STRAP

Abraham Schwalberg, Brooklyn, N. Y.

Application March 20, 1939, Serial No. 262,915

16 Claims. (Cl. 224—4)

This invention relates to wrist watch straps and particularly to the construction of the ends thereof which are connected to a wrist watch.

Heretofore, wrist watch straps were usually constructed of two-ply material, one ply being elongated and doubled back at the end of the strap to form an eye for connection with the watch or with the buckle usually provided upon one of the straps. The corrosive action of the acid in perspiration frequently undermined the strength of the stitching which held the plies of a strap together and after only a short period of use, the strap became frayed and unsightly. The doubled-over end of one of the plies had a certain weakness inherent in the type of leather used in the plies and for this reason the straps wore poorly. Seeking to obviate the above faults, attempts have been made to form the strap of a single thickness of relatively thick leather, skiving thin one end of the strap and doubling over this thinned end to form an eye for connection with the watch. This construction was also faulty in that the thin portion of the relatively thick leather was weakened and the eye would become disrupted either along the stitching which secured it in place or at the lateral edges thereof, the latter fault being due to the almost continual friction of the wrist watch pin disposed in the eye.

The present invention, recognizing the above faults, seeks to provide a watch strap having long wearing qualities, of pleasing appearance, and relatively inexpensive of manufacture.

Of importance is the ease with which a wrist watch strap may be connected or removed from association with a watch, and for this reason the invention also seeks to provide simple and efficacious means for effecting these functions.

Also in keeping with the above, the invention seeks to provide a wrist watch strap in which the strap itself is made of a single ply of thick leather and the eye for connection with the watch, is formed in a thinner, yet commensurately stronger, strip of leather affixed to the strap.

The invention also contemplates the provision of a metallic fitting in the end of the strap for increasing its wearing properties.

The manner of applying the metallic fitting to the strap whereby it is hidden from view and serves either to only strengthen the strap end or to both strengthen and provide detachably securing means for the strap, also form a material part of this disclosure.

The above and other objects of the invention

will become more clearly apparent from the following description which is based on the accompanying drawing in which is illustrated forms of the invention at present preferred.

5 In the drawing:

Fig. 1 is a front view of a strap embodying the invention as applied to a wrist watch.

Fig. 2 is an enlarged, partly broken away front view of one of the strap ends incorporating a metal fitting therein.

Fig. 3 is a longitudinal sectional view thereof.

Fig. 4 is a transverse sectional view as taken along the line 4—4 of Fig. 2.

Fig. 5 is a view similar to Fig. 3 of an alternate 15 form of construction.

Fig. 6 is a face view thereof in open condition.

Fig. 7 is a view similar to Fig. 5 showing a modified form of metal fitting.

Fig. 8 is a similar sectional view showing another application of the metal fitting.

Fig. 9 is a front partly broken away view of a strap end showing a modification of the structure illustrated in Fig. 2 and connected with a wrist watch of slightly different construction from that shown in Fig. 1.

Referring now to the drawing, and more particularly to Figs. 1 through 4, I have there shown a conventional form of wrist watch 10. As is usual, the watch is provided with integral or removable end pins or lugs or the like 11, said pins serving to engage the straps 12 and 13 so that the watch may be suitably carried on the wrist of the wearer.

The straps 12 and 13 each comprise a length of leather 14 of a substantial thickness. This length of leather may be made of cowhide, reptile skins, pig skin, etc., it being the purpose of the invention to provide a long-wearing, sturdy, not easily frayed, yet pliable length of leather.

30 For connection with the pins 11 of the watch 10, the length of leather 14 of each strap 12 and 13, is preferably provided with an eye 15 formed in a leather strip 16, doubled on itself to provide ear portions 17, each engaged against opposite 35 faces of the length of leather, and stitched thereto as at 18. It will be noted that the eye thus formed is disposed beyond the end of the length of leather 14.

The leather strip 16 is preferably considerably 40 thinner than the length of leather 14 to obviate undue bulkiness of the strap end and for the further reason that the space between the watch lugs or pins 11 and the watch case is frequently quite narrow and will permit the passage 45 therethrough of only quite thin leather. It is

desirable to employ a thin leather so formed during its preparation and having comparatively greater strength for its thickness than has a commensurately thin piece of the thick leather above mentioned. Certain kid, goat, reptile, and calf skins are suitable for this purpose.

The straps 12, 13 are provided with a metallic fitting 20. In this embodiment of the invention, the fitting is formed with a plate portion 21 engaged against one face of the strap 14 and provided with means such as the prongs 22 passing through slits 23 in the strap 14 and bent as at 24 to engage against the other face of said strap. The fitting 20 is thus effectively and securely affixed to said strap.

A metallic eye 25 is formed on the end of the fitting and disposed beyond the end of the strap 14, said eye being preferably extended laterally as at 26 so that it is substantially the length of the watch pin 11.

This structure is quite advantageous and may be readily connected and disconnected from a watch, removal of the pins 11 being entailed. It may be desirable, however, to arrange the strap for removable association with the watch without removing the pins 11 thereof, the forms of the invention shown in Figs. 5, 6, and 7 contemplating this arrangement.

In the form of the invention shown in Figs. 5 and 6, the construction follows that shown in Figs. 1 through 4, but in this instance the leather strip 16 has only one ear 17 stitched to the strap 14, the other ear 17a being capable of being opened up to expose the metal eye 25a which, in this case, is somewhat open in the form of a hook so a pin 10 may be snapped into and out of engagement therewith. The ear 17a is also slotted at 27 for protrusion therethrough of the prongs 22 which may then be bent to engage against the exposed face of said ear.

The structure of Fig. 7 is similar to that of Figs. 5 and 6, the eye 25a being omitted and the fitting 20a serving only to removably hold the ear 17a.

It is evident from the description of the last two forms of the invention that by simply straightening the prongs 22 and opening out the ear 17a, the strap may be removed from connection with the watch. The above feature is quite desirable because of frequent freezing of the pins in their bearings in the watch or where the pins or lugs are permanently fixed.

In the embodiment shown in Fig. 8 the metal insert 20b, by means of its prong 22 and the bent portion thereof 24, may be held in fixed position on the end of the strap 14. The fitting, in this instance may be provided with one or more prongs 28 each having an end portion 29 for detachably holding the bent ear 17a of the leather strip to form the eye 15.

Ofttimes a watch is provided with a central lug as shown in Fig. 9. In this case, the eye 25 of the metallic fitting and the eye 15 of the leather strip are both notched as at 30 for accommodation of said central lug. Where a strap of the form shown in Fig. 7 is to be applied to such a watch, it is evident that the eye 15 is weakened by the provision of this notch. Hence, it becomes further apparent that the leather from which the strip 16 is formed must be commensurately stronger for its thickness than is a similarly thin skived portion of the leather of the strap 14.

From the foregoing it is apparent a simple construction, in several forms of embodiments,

for rendering watch straps stronger, and more easily mountable and dismountable, has been provided; that the straps present a neat, trim, and appealing appearance; that the construction lends itself to further enhancing the appearance of the straps by the use of differently colored or surfaced leathers; and that there has been produced well designed straps to meet all requirements of practical use.

10 While there have been disclosed specific forms of the invention, it should be understood that it is not intended to limit the invention thereto but to claim said invention as broadly as may be permitted by the state of the prior art and the scope of the appended claims.

I claim:

1. A watch strap comprising a thick length of leather, a member forming an eye for connection with a wrist watch stitched to an end of said strap and comprising a short relatively thin strip of leather having a tensile strength greater than that of a commensurately thin portion of said relatively thick leather, and a metallic member secured to said thick length of leather and having a metal hook disposed beyond the end of said thick length of leather and within the eye formed by said mentioned strip of leather.

2. A watch strap comprising a length of leather slotted adjacent an end thereof, a metallic member positioned against one face of said length of leather and having prongs projecting through said slits, the projecting portions of said prongs being bent to engage the other face of said length of leather, a hook for connection with a wrist watch formed on said metallic member and disposed beyond the mentioned end, a short strip of leather substantially thinner than said length of leather and having end portions disposed against both faces thereof to form a cover for said metallic member and its hook, and means for securing said strip of leather to said length of leather.

3. A watch strap comprising a length of leather slotted adjacent an end thereof, a metallic member positioned against one face of said length of leather and having prongs projecting through said slits, the projecting portions of said prongs being bent to engage the other face of said length of leather, a hook for connection with a wrist watch formed on said metallic member and disposed beyond the mentioned end, a covering member for said metallic member comprising a short relatively thin strip of leather bent on itself to form a hook disposed about said metal eye and having portions each disposed against the opposite faces of said length of leather to cover the remainder of the metallic member, and a line of stitching affixing said covering member to said length of leather and arranged around three sides of said metallic member.

4. A watch strap comprising a length of material having a pair of spaced slits adjacent an end thereof, a metallic member positioned against one face of said length of leather and having prongs protruding through said slits, and a relatively thin strip of material which is shorter than said length of material and has a tensile strength greater than that of a commensurately thin portion of said length of material, said strip having one end disposed against one face of said length of leather and affixed thereto to cover said metallic member, said strip of material being bent to form a pin engaging hook disposed beyond the end of the length of material, said bent portion having spaced slits in register

with the previously mentioned slits and through which the protruding portions of the mentioned prongs project, and said prongs being bent to engage against the exposed face of said bent portion of the strip to detachably hold said bent portion in eye forming position.

5. A watch strap comprising a length of material having a pair of spaced slits adjacent an end thereof, a metallic member positioned against one face of said length of material and having prongs protruding through said slits, a pin engaging hook formed on said metallic member and disposed beyond the end of said length of material, and a short, thin strip of leather having one end disposed against one face of said length of material and affixed thereto to cover said metallic member, said strip being bent to form a covering hook for the hook of the metallic member, the bent portion of said strip having spaced slits in register with the previously mentioned slits and through which the protruding portions of the mentioned prongs project, and said prongs being bent to engage the exposed face of said bent portion of the strip to detachably hold said bent portion in eye forming position.

6. In a strap formed of a single piece of material and having a pair of spaced slits adjacent an end thereof, a metallic member disposed against one face of said piece of material and having prongs projecting through said slits, and a strip of material which is shorter and thinner than said piece of material and has a tensile strength greater than that of a commensurately thin portion of said piece, said strip positioned against said face and permanently secured thereto, said strip being bent to form an eye beyond the mentioned end and formed with a pin engaging portion parallel to the permanently secured portion, the mentioned parallel portion having slits in register with the slits in the piece of material and through which the prongs also project, and said prongs being bent to engage against the exposed face of said parallel portion of the strip to detachably hold said latter portion in eye forming position.

7. In a strap formed of a single piece of material and having a pair of spaced slits adjacent an end thereof, a metallic member disposed against one face of said piece of material and having prongs projecting through said slits, a pin engaging hook formed on said metallic member and disposed beyond the mentioned end, and a short, thin strip of material positioned against said face and permanently secured thereto to cover said metallic member, said strip being bent to form an eye covering the hook of said metallic member and formed with a portion parallel to the permanently secured portion, the mentioned parallel portion having slits in register with the slits in the piece of material and through which the prongs also project, and said prongs being bent to engage against the exposed face of said parallel portion of the strip to detachably hold said latter portion in eye forming position.

8. An end fitting for watch straps and the like and having a short, thin covering strip comprising a flat plate, spaced prongs integrally formed on the lateral edges of said plate and adapted to pass through slits formed in the strap, and an eye formed at one end of said plate, said eye extending laterally of said lateral edges and adapted for connection with a wrist watch and said prongs being adapted to detachably engage said covering strip.

9. A watch strap comprising a length of leath-

er of considerable thickness, a metallic fitting secured to an end of said length of leather, spaced aligned eyes formed on said fitting and disposed beyond the said end, a short, thin strip of leather doubled on itself to form a cover for said eyes and for the metallic insert, and stitching securing the parallel ears of said doubled strip to respective faces of said end of the length of leather, the mentioned eyes being adapted for connection with a wrist watch having a lug disposed therebetween.

10. The combination with a wrist watch having a central end lug and a strap connecting pin, of a watch strap comprising a length of leather, a metallic fitting secured to an end of said length of leather, and provided with eyes connected with said pin, said eyes being aligned and on each side of said central lug, a short, thin strip of leather doubled on itself to form a cover for said eyes and said fitting, and stitching securing the parallel ears of said doubled strip to respective faces of said end of the length of leather, said strip of leather being formed with an opening for accommodation of the mentioned central lug.

11. A watch strap comprising a length of leather or the like, a metallic member disposed against one surface of said strap and adjacent an end thereof, prong means on said member passing through said strap intermediate its lateral edges, and a strip of leather or the like secured to the mentioned strap surface to cover said metallic member and bent to engage the other surface of said strap and to form a watch-engaging loop disposed beyond the said end of the watch strap, said prong means being adapted to pass through the said bent portion of said strip of leather and to removably hold the same in position, said strip of leather being shorter and thinner than said length of leather and having a tensile strength greater than that of a commensurately thin portion of said length of leather.

12. A watch strap comprising a length of leather or the like, a metallic member disposed against one surface of said strap and adjacent an end thereof, prong means on said member passing through said strap intermediate its lateral edges, a watch-engaging eye formed on said metallic member and disposed beyond said mentioned strap end, and a short, thin strip of leather or the like secured to the mentioned strap surface to cover said metallic member and adapted to be bent about said eye and to be detachably held against the other surface of said strap by said prong means.

13. In a watch strap, a strap-end eye formed of a doubled-back leather strip, one leg of said strip being permanently secured to said strap, and a metallic fitting disposed between said strap and the mentioned leg and formed with means passing through said strap and adapted to detachably engage the other leg of said strip to detachably hold the same in position against the strap, said strip being shorter and thinner than the strap to which it is secured and having a tensile strength greater than that of a commensurately thin portion of said strap.

14. A watch strap comprising a length of material provided with slits adjacent one end thereof, a short, thin strip of material bent to form two legs and an eye, said eye being disposed beyond the mentioned end and said legs being disposed against opposite surfaces of said length of material, and a metallic fitting disposed between one of said surfaces and the leg associated therewith, said metallic fitting being provided with prong

means detachably engaged in the mentioned slits and with a hook disposed within the eye of said strip of material for engagement with a wrist watch.

15. In a watch strap or the like, a length of material, a member comprising a U-shaped strip having one leg secured to one face at one end of said length of material and formed with a pin engaging eye disposed beyond said end of the length of material, a fitting disposed between the mentioned leg and said face of the length of material and completely covered thereby, said fitting being provided with prong means passing through and protruding beyond the other face of said length of material, the other leg of said U-shaped strip being slotted for separable engagement with said protruding prongs whereby said watch strap is separably engaged with the mentioned pin, said strip being shorter and thinner than said length of material and having a 20

tensile strength greater than that of a commensurately thin portion of said length.

16. In a watch strap or the like, a length of material, a member comprising a short, thin U-shaped strip having one leg secured to one face at one end of said length of material and formed with a pin engaging eye disposed beyond said end of the length of material, a fitting disposed between the mentioned leg and said face of the length of material and completely covered thereby, an eye formed on said fitting and disposed within the mentioned eye of the U-shaped strip, said fitting being provided with prong means passing through and protruding beyond the other face of said length of material, the other leg of said U-shaped strip being slotted for separable engagement with said protruding prongs whereby said watch strap is separably engaged with the mentioned pin.

ABRAHAM SCHWALBERG.
